2 Claims. (Cl. 215—39)

This invention has reference to caps or the like adapted to permanently close an aperture for instance at the top of a container, bottle or the like.

It has for its object to provide a cap or similar closure which can easily be applied to such aperture and particularly to the neck portion of such a container or bottle by crimping or staking it over a widened collar, flange or like projection or projections therefrom, at normal atmospheric temperatures.

It is known that caps of aluminum, brass, bronze or other easily deformable metals having a wall thickness of the order of 1 mm. could be so applied at normal temperature, but metal caps have the disadvantage that they are liable to be corroded or to be otherwise attacked by the liquid contents of such containers or bottles and, besides this, galvanic action may occur if metal caps are used on aluminum or other metal containers.

Tests carried out with numerous synthetic materials which can be moulded or made otherwise to the required shape have shown that it is not possible with any of the plastic materials conventionally used for moulding or otherwise producing rigid articles to effect the crimping or staking the flange of caps made of such a material having wall thicknesses of the order of 1 mm. at normal, i.e. at atmospheric temperatures. All thermosetting or thermo-hardening materials are obviously un-suitable for this purpose as they lack the required ductility irrespective of the ambient temperature. Thermoplastic materials, on the other hand, require for crimping a considerably elevated temperature. The heating of the caps, however, prior to their application to container or bottle necks or tops would not only be a cumbersome procedure requiring special equipment, but it would also in most cases be most inconvenient as the container or bottle would be heated at the same time at least locally. Many types of containers, particularly those which have been labelled or otherwise been finished, prior to being capped, cannot be subjected to heat. The same considerations would apply to containers filled with liquid or other substances, prior to capping, with a view to the effect the heat may have on their contents.

Surprisingly it has been found that the flanges of caps or similar closures made of acetal resin, which is a highly crystalline and stable form of polymerised formaldehyde, and having a wall thickness within the range from about $\frac{1}{4}$ mm. to about 3 mm. can easily and effectively be deformed by crimping or staking on to or over a flanged, collared or otherwise widened container aperture by a crimping pressure applied to said flanges at normal atmospheric temperatures. This property of acetal resins has been newly established by the applicant in numerous tests, having been unknown up to present time to manufacturers of these resins and to research workers in the field of plastic materials, generally.

Acetal resin is sold, for instance, by E. I. du Pont de Nemours of U.S.A. under the trade name "Delrin."

Caps for containers made of acetal resin may be produced in various ways, for instance by injection moulding, by extrusion or by machining from rods or discs, depending on the required size and/or wall thickness.

In order to more particularly describe the invention

2

reference is made to the accompanying drawing which, by way of example only, illustrates a specific embodiment of a cap for use on a conventional aerosol bottle. In said drawing—

5 FIG. 1 is a cross-sectional view of the cap taken on line I—I of FIG. 2,

FIG. 2 is a view of the cap from underneath,

10 FIG. 3 is a cross-sectional view of the cap similar to FIG. 1, with the cap placed on the top of an aerosol bottle, the figure also illustrating a tool for crimping the cap over the top of the bottle, and

15 FIG. 4 is a fragmental view showing the bottle in elevation with the cap crimped over the top.

The cap 10 shown in FIGS. 1 and 2 includes a disc-like portion 11 which may be flat as shown and is provided with a central aperture 12, and with two concentric flanges 13 and 14. Flange 13 is an interior flange the inner diameter of which corresponds to the outer diameter of the shell of a valve mechanism for the aerosol bottle on which the cap 10 is to be used, whereas the flange 14 is an outer flange for mounting the cap 10 on the top of said bottle.

20 FIG. 3 illustrates the cap 10 in position on the top portion of a bottle 16 with the shell 21 for the valve mechanism retained in position within the cap by the interior flange 13, and with the conventional discharge tube 15 projecting upwardly from the shell 21 through the aperture 12 of the cap 10.

25 In the example illustrated the aerosol bottle is made of glass and the extreme end portion 22 of its top has a diameter of about 19 mm. and an interior diameter of about 12 mm., the top being provided with an annular recess or undercut 23 at a distance below the extreme end portion 22 which is less than the height of the outer flange 14 of the cap 10. Therefore, when the cap 10 is placed in position on the bottle top, the free end portion or edge of the flange 14 faces the annular recess 23. The interior flange 13 of the cap may be a clearance fit within the aperture of the bottle top 22, and the outer flange 14 is a neat fit on the end portion 22 of the bottle top.

30 According to the invention the cap 10 is made of acetal resin and, preferably, of acetal resin made and sold by E. I. du Pont de Nemours of U.S.A. under the trade name "Delrin." In the example shown the outer diameter of the outer flange 14 of the cap is 22.5 mm. and its wall thickness 1.5 mm.

35 The cap 10 is secured to the extreme end portion 22 of the bottle top by a crimping operation carried out with a crimping collet including a plurality of tongues 17 which are arranged symmetrically about a central axis and the free ends of which tend to diverge from said axis, and an annular element 18 which surrounds the tongues and is so arranged relative thereto that its axial displacement towards the free ends of the tongues 17 forces these free ends inwardly towards the central axis of the collet.

40 The crimping operation is effected, as shown in FIG. 3, by first placing the cap 10 on the end portion 22 of the bottle top as described above, then placing the collet over the cap so that the tips of the tongues 17 face the free edge of the outer flange 14 at locations opposite the recess 23 and, finally, by moving the annular element 18 towards the cap 10 which causes the tongues 17 to move radially inwardly and thereby to deform the free edge of the flange 14 in the manner illustrated in FIG. 4, the tongues producing in said edge a series of indentations 20.

45 Since the cap 10 is made of "Delrin" or an equivalent acetal resin, as stated above, the crimping can be effected at normal atmospheric temperature. In this operation the outer flange 14 of the cap is plastically deformed without

the occurrence of cracks or other irregularities in the flange 14 and/or any other part of the cap 10.

Tests carried out with aerosol containers and caps of the dimensions stated above and made of acetal resin ("Delrin") revealed that a tight seal was obtained by crimping the cap over the open top or neck of the containers in the manner described above. During these tests the filled bottles with the caps crimped on were immersed in water heated to a temperature of 70° C. and were retained in the warm water for periods of 9 minutes and over, so that interior pressures of up to 21 kg./cm.² were produced inside the containers. Even at that pressure the seal remained perfect, no leakage of aerosol occurring.

These tests proved adequately that aerosol containers in which normally only pressures up to 5 kg./per cm.² occur could safely be sealed with acetal caps crimped or staked on as described, by a process carried out at the ambient atmospheric temperature, i.e. by a cold process.

In a further series of tests it was established that the cold crimping process can be used with equal advantage on acetal resin caps having flanges or skirts of wall thicknesses varying between about 1/4 mm. to about 3 mm.

When applying a cap made of acetal resin in accordance with the present invention to a bottle or container by crimping or staking, care must be taken to so adjust the crimping pressure to the wall thickness of the cap flange or skirt, that the specific pressure within the material of the flange or skirt during the crimping or staking operation should be above the elastic limit of the cap material.

In the light of the foregoing description, it will be clear to the expert that the invention is applicable to all types of containers having an open neck with an annular end portion projecting over a recess, undercut or the like, and is therefore not limited to the sealing of aerosol containers. Because of the metal-like mechanical properties of acetal resin it is possible to shape the cap as may be required, either as a plain cap or as a combined cap and valve housing, particularly when the cap is intended for use on aerosol containers.

Caps made of acetal resin according to the present invention are entirely non-corrosive, and galvanic action between the cap and the container is entirely excluded due to the fact that acetal resin is essentially an electric insulator.

Acetal resin can be made to various colours and, as caps or similar closures can be shaped variously as well, they can be made to meet different requirements of appearance and sightliness as well.

From the foregoing description it will be understood that the present invention relates not only to a cap or like closure for use on a container, bottle or the like, but also has reference to a method of making a closed container, bottle or the like which method includes the steps of, firstly, selecting a container or bottle having a neck portion with an aperture therein, a recess or undercut in the outer surface of said neck portion and an end of said neck portion which surrounds the said aperture and projects over the said recess or undercut; then, applying over said aperture a cap of acetal resin, said cap having a flange or skirt which when so applied surrounds and encloses said end

portion and, finally, crimping or staking the free edge of the said flange or skirt at normal atmospheric temperature around the said end and into the said recess or undercut for rigidly securing the cap to the said neck portion.

It will further be appreciated that the invention also encompasses the container, bottle or the like if closed with a cap of acetal resin by the said method, in the manner described above.

What I claim is:

1. A closure for a container having a neck portion forming a rim at its top with an opening defined within the rim and a recess defined in the outer surface of the neck portion below said rim, comprising, a cap made of acetal resin having a flat portion adapted to close at least a portion of the opening of the container and including a skirt portion connected to the circumference of the flat portion and extending downwardly beyond the recess of the neck portion of the bottle, said cap having a wall thickness of from about between 1/4 mm. to 3 mm. and permitting the skirt portion to be crimped to direct the acetal resin material into the recess of the container, said acetal resin material being capable of retaining its seat on the container recess when subjected to pressures of approximately 5 kilograms per square centimeter.

2. A closure for a container, particularly for an aerosol container adapted to be subjected to pressures of five kilograms per square centimeter, said container having a neck portion forming a rim at its top with an opening defined within the rim and a recess defined in the outer surface of the neck portion below said rim, a cap made of acetal resin with a top portion closing a portion of the opening of said container and having a central opening therein for receiving a projecting part of an aerosol element, a first flange portion extending from said flat top portion into the interior of said container and a second flange portion connected circumferentially to said flat top portion and fitted over the exterior surface of the rim of said container, said cap being of a thickness of from about 1/4 mm. to 3 mm. and being capable of being crimped with portions thereof and being capable of being forced into the recess of said container, said acetal resin being capable of withstanding the pressures within said container without causing the crimped portion to become loosened from the recess of the container.
